UNITED STATES PATENT OFFICE.

JOB E. JONES AND WILLIAM G. HODGE, OF FORBUSH, IOWA.

MEANS FOR PROTECTING CAR DOORS AND SIDES.

SPECIFICATION forming part of Letters Patent No. 610,990, dated September 20, 1898.

Application filed August 14, 1897. Serial No. 648,208. (No model.)

To all whom it may concern:

Be it known that we, JOB E. JONES and WILLIAM G. HODGE, citizens of the United States, residing at Forbush, in the county of Appanoose and State of Iowa, have invented certain new and useful Improvements in Means for Protecting the Sides and Doors of Cars; and we do hereby declare the following to be a full, clear, and exact description of the invention, such as will enable others skilled in the art to which it appertains to make and use the same.

This invention relates to an improvement in means for protecting the sides and doors of cars, as embodied in the construction hereinafter described, and definitely pointed out in the claims.

The invention consists, primarily, in an apparatus or means for protecting the sides or doors of freight-cars, and it is designed more particularly for use in connection with that class of cars wherein the freight or material is discharged in bulk into the car—such as coal, lime, grain, &c.—and the purpose of the invention is to provide a reinforcing or abutment means against which the material may strike as it is discharged from the hopper or chute into the car.

In filling cars with coal or lime it is often necessary to place boards across the doorway inside to prevent the material from striking the door proper, thereby damaging the same. In the majority of cases the coal or lime is projected into the car through the doorway at one side toward the opposite door, which usually is required to resist the impact of the incoming material. To prevent injury to the sides or doors of the car, we have designed and invented the present apparatus.

In the drawings, wherein like reference-letters designate corresponding parts, we have shown for the convenience of illustration and description a form of apparatus for accomplishing the purpose above stated, and in which—

Figure 1 is a sectional elevation of a car, showing the apparatus in operative position and in elevation, the protector being shown in elevated position in dotted lines. Fig. 2 is a modification. Fig. 3 is a detail view of one of the yielding connections. Fig. 4 is a side elevation.

We have shown our apparatus as applied to an ordinary track-scale; but it is to be understood that it may be employed without being connected to a scale, but in any manner convenient or desirable. When mounted on a scale, it is free to move therewith and permits the car to be moved.

In the drawings, A represents a scale-plate-form, and B the track-rails mounted thereon. Between the track-rails and platform are secured the bars A', forming extensions of the supporting-arms B', which latter extend upwardly at the side of the track and are fulcrumed on a block A², mounted on the platform. On the outer ends of the bars B' are secured the uprights B², which extend up to a plane above the top of the car.

C designates a series of four arms pivotally supported in boxes c on the upright B², which boxes are secured to the upright by bolts C', passing therethrough, their inner ends being threaded through spiral springs C², resting against the uprights on one end and a head 75 or washer c at the other end. By this means a slight yielding or transverse movement of the boxes is permitted. On the opposite ends of the arms C is secured a bumper or abutment D, the same being connected thereto by 80 suitable hinges d. The arms C are spaced apart an equal distance and are connected with the abutments at opposite corners, and owing to the pivotal connection are permitted a vertical movement, so that the abutment 85 or buffer may be properly adjusted. To adjust the same, we conveniently employ a rope or cable E, passing around a sheave or pulley segment E', mounted in the upper end of the upright, the cable extending to the weighing-house or any other convenient point within the reach of the operator. To raise the buffer, it is only necessary to draw on the cable and to then attach the latter to any stationary object or device which will maintain the buffer 90 in an elevated position, as shown in dotted lines, Fig. 1. The weight of the buffer will in itself be sufficient to cause it to drop when it is desired to lower it.

When the apparatus is attached to a scale, 100 it is necessary to brace the uprights at the top, in which case we connect to the upper portion of the upright bars F, having a pivoted or knuckle connection f with the up-

rights, and their opposite ends being pivotally connected to a lever F' , mounted on the stationary upright G , a rope or cable being attached to the upper end of the lever, as at 5 g , which may extend back into the weighing-room or other convenient position in reach of the operator. By loosening the rope g the uprights B^2 may easily move down as the load increases, the operator connecting the rope 10 g to a fixed stop or hook, so as to limit the movement.

In operation as the car is brought onto the scale, the doorway being opposite the protector, the operator allows the latter to fall 15 until it rests either against the outer face of the car or in the doorway, and as the material is dumped into the car it strikes the abutment, side of the car, or a door, should one be in front of the abutment. Thus the force 20 and impact will be resisted by the abutment, thereby preventing the door or side from being forced out or broken by the outward pressure. We have found it desirable to have the abutment somewhat yielding, and to this 25 end provide the springs C^2 above described. It is apparent that the abutment can be used in connection with a supplemental door, as L , which is located inside the car across the opening.

30 In Fig. 2 we have shown a slightly-modified form wherein the lower arms, which support the abutment, are formed into two sections, united by a knuckle or rule joint. In this particular construction it is only necessary 35 to break the joints downward, and the abutment can be withdrawn from the car in a downward direction. We have shown in this modification also a device wherein the hoisting-cable is not necessarily required, the 40 spring or yielding connection also being dispensed with. In other respects the connection is the same as in the former case.

It is apparent that in either construction 45 the abutment can be used with good effect to brace or support the side of a car, as the same is maintained in a vertical position when being placed against the side or outer door of a car and will act as a support against the internal pressure.

50 The uprights, as is obvious, may be mounted on a movable truck at the side of the car or may be fixed stationarily at any predetermined point. We therefore desire it understood that while we have shown two forms of 55 the device, yet we are aware that many changes in the construction and arrangements of the parts can be made and substituted for the same without departing from the nature and principle of our invention.

60 Having thus described the invention, what we claim as new, and desire to secure by Letters Patent, is—

1. In a protecting device for the sides of cars while being loaded, the combination with

suitable supporting members arranged at the 65 side of the track, of an abutment, and means for securing the abutment to the supporting members comprising pivotal arms, substantially as described.

2. In a protecting-buffer for the sides of 70 cars while being loaded, the combination with a support arranged at the side of the track, of a buffer member, and means for connecting and supporting the buffer member from the support comprising a series of pivoted 75 members arranged to vary the position of the buffer relative to the supports upon the movement of the connecting members, substantially as described.

3. In a device for protecting the sides of 80 cars while being loaded the combination with a support, of a series of arms pivoted thereto and a buffer member pivoted to the outer ends of the arms, substantially as described.

4. In a device for protecting the sides of 85 cars while being loaded the combination with a support arranged at the side of the track, of a buffer member, and a pivotal yielding connection between the support and buffer member, substantially as described. 90

5. In combination with a support, of a series of toggle-arms secured thereto, and a buffer pivotally supported on the outer ends thereof, substantially as described.

6. In combination with a support, of a series of arms pivoted thereto, a buffer pivotally connected to the outer ends of the arms, and means for raising the arms and buffer, substantially as described.

7. The combination with a support, of a series of journal-boxes yieldingly supported thereon, arms mounted in the boxes, and a buffer pivotally secured to the outer ends of the arms. 100

8. The combination with a scale, of a support extending out therefrom and supported thereby, uprights on the support and an adjustable buffer carried by the uprights, substantially as described. 105

9. The combination with a scale, of supports thereon extending out beyond the same, uprights carried by the supports, an adjustable buffer carried by the uprights, and an adjustable brace for the upper ends of the uprights, substantially as described. 110

10. In a device for protecting the sides of cars while being loaded, the combination with a track, of a buffer, means at the side of the track for supporting the buffer, and means for moving the buffer toward and from the 115 plane of the track, substantially as described.

In testimony whereof we affix our signatures in presence of two witnesses.

JOB E. JONES.

WILLIAM G. HODGE.
